ATTORNEY.

UNITED STATES PATENT OFFICE.

FRED W. CLARK, OF UTICA, NEW YORK.

ABDOMINAL SUPPORT.

SPECIFICATION forming part of Letters Patent No. 747,139, dated December 15, 1903.

Application filed December 5, 1902. Serial No. 133,939. (No model.)

To all whom it may concern:

Be it known that I, FRED W. CLARK, of Utica, in the county of Oneida and State of New York, have invented certain new and useful Improvements in Abdominal Supports; and I do hereby declare that the following is a full, clear, and exact description of the invention, which will enable others skilled in the art to which it appertains to make and use the same, reference being had to the accompanying drawings, and to the letters and figures of reference marked thereon, which form part of this specification.

The object of my invention is to provide an abdominal support which is suitable and effective for its purpose and can be worn with little or no inconvenience and discomfort.

In the drawings, Figure 1 shows a perspective view of a support of my improved construction. Fig. 2 shows a front view of the front portion with the band extended in a flat plane. Fig. 3 shows a rear view of the back portion in a similar manner. Fig. 4 shows a section of the front portion, taken on line A B of Fig. 2. Fig. 5 shows a section of the rear portion, taken on line C D of Fig. 3.

Referring to the reference letters and figures in a more particular description, I indicate the front portion of the band, which is made to conform to the figure of the wearer and is comparatively wide vertically. The rear portion 2 of the band is narrower and adjustably connected with the forward portion by elastic straps 3, with buckles 4 provided upon one or both sides of the band. The front part 1 of the band is of non-elastic material—such as canvas, for instance—and has secured thereto or inlaid between the walls or ply the horizontally-extending flexible bands or ribs *a a*, &c. These ribs *a a* are of whalebone or similar material and normally tend to extend in a straight line. The rear or back part 2 is also constructed of in-

elastic material similar to the front portion 45 and is provided with vertically-extending flexible stays or ribs *b b*, similar to *a a*. In connection with the band there is employed a pair of leg-bands 55, preferably opening at the outer sides and provided with an elastic strap 6 and buckle 7. The leg-bands are connected with the front portion 1 of the main body-band by a short elastic strap 8 and a buckle 9 and are connected at the rear with the back portion 2 of the main body- 55 band by a comparatively long elastic strap 10, whereby the leg-bands are allowed to assume an angular position with reference to the main body-band.

The longitudinal ribs *a* in the front portion of the body-band tend to exert a pressure on the abdomen, while permitting a comparatively free bend of the body. The vertical ribs *b* in the back band serve to hold the band portion 2 extended vertically and 65 obviates a tendency to draw together into a narrow insufficiently-wide band. Through the medium of the straps 3 these ribs also tend to keep the front portion properly extended vertically. 70

What I claim as new, and desire to secure by Letters Patent, is—

In an abdominal support, a front band portion conforming to the figure, and a back portion connected by elastic straps at the 75 sides with the front portion, leg-encircling straps connected at the front by a short elastic strap to the said front portion and connected at the rear by elongated elastic straps with the said back portion, substantially as 80 set forth.

In witness whereof I have affixed my signature, in presence of two witnesses, this 28th day of November, 1902.

FRED W. CLARK.

Witnesses:

E. WILLARD JONES,
MAY CLARK.
